UNITED STATES PATENT OFFICE.

ZACHARY T. MILLER, OF BLISS, OKLAHOMA.

STRAP-END-ATTACHING DEVICE.

1,407,291.

Specification of Letters Patent. Patented Feb. 21, 1922.

Application filed April 15, 1921, Serial No. 461,547. Renewed January 18, 1922. Serial No. 530,232.

To all whom it may concern:

Be it known that I, ZACHARY T. MILLER, a citizen of the United States, residing at Bliss, in the county of Noble and State of 5 Oklahoma, have invented certain new and useful Improvements in Strap-End-Attaching Devices; of which the following is a specification, reference being had therein to the accompanying drawing.

10 This invention provides economical and efficient means for attaching a strap-end to a ring, loop, buckle part, or the like.

It is an object of the invention so to form such an attaching means of bendable 15 sheet metal that it may be easily placed in association with a strap or the like and the part to be held thereby.

When considered in connection with the description herein, the characteristics of the 20 invention will be apparent from the accompanying drawing, forming part hereof, wherein an embodiment of the invention is disclosed, for purposes of illustration.

Although the disclosures herein exemplify 25 what now is considered to be a preferable embodiment of the invention, it is to be understood that it is not the intention to be limited necessarily thereto in interpretation of the claims, as modifications and adaptations within the limits of the claims can 30 be made without departing from the nature of the invention.

Like reference-characters refer to corresponding parts in the views of the drawing, 35 of which—

Fig. 1 is a view of the device in association with a strap and metal ring;

Fig. 2 is a view of the device with a part 40 bent over the ring and ready to receive the strap; and

Fig. 3 is a view of the blank from which the device is formed.

In the formation of the article, blanks of substantially the shape shown by Fig. 3 45 are cut or struck from strong bendable sheet metal stock.

Such a blank includes a central web 4, a covering side portion 5, and a clamping side portion 6, all presenting a somewhat elongated substantially rectangular surface. An 50 extension 7, which is to form a loop member, projects at substantially right angles from the web of the elongated part of the blank. Prongs 8 are struck out to extend 55 from surfaces of the parts 6 and 7 before the blank is bent.

When the article to be formed from such a blank is to be associated with a ring, loop, or the like, the part 7 is passed thereinto, either before or after partial bending, and 60 it is bent over one side of the ring, loop, or the like at a place removed from the edge of the web and down against the web.

The end of the strap or the like to be secured to the ring, loop, or the like is laid 65 on the bent-over portion of the part 7, the clamping part 6 then is bent over and down against the strap or the like, and then the covering part 5 is bent over and down against the part 6.

70 The prongs are disposed in such manner in the parts 6 and 7 that they extend into the end of the strap or the like when the parts are bent into place, and they thus obviate liability of the held part to slip 75 from between the parts that are clamping it.

In order to make certain the engagement of the prongs in the held part and to produce a comparatively flat article, the bent-over parts may be hammered down into 80 place.

Preferably, although not necessarily, the part 5, which is the last to be bent over and down, should be long enough to extend over the openings made in striking out the prongs 85 from the part 7, in order that rough places that may result from such operation may be covered and the completed article may be smooth.

Before laying the end of the strap or the 90 like on the bent-over part 7, it is advantageous to bend the parts 5 and 6 to positions substantially at right angles to the web 4, as shown by Fig. 2, in order to afford a guide for positioning the held part on the bent-over part 7, and then to bend and hammer down the parts 5 and 6 as described.

Having thus described my invention, what I claim as new, and desire to secure by Letters Patent, is—

1. As a connecting device for an end of a strap or the like, a piece of bendable sheet metal having a central web, a leg extending therefrom arranged to be extended through and bent over a side of a ring or the like 100 and down against the web, a clamping part extending from said web arranged to be bent over and down against a strap or the like on said bent-over leg, and another part on said web arranged to be bent over and 105 down against said clamping part.

2. As a connecting device for an end of

a strap or the like, a piece of bendable sheet metal having a central web, a leg extending therefrom arranged to be extended through and bent over a side of a ring or the like and down against the web, a clamping part extending from said web arranged to be bent over and down against a strap or the like on said bent-over leg, and another part on said web arranged to be bent over and down against said clamping part, said leg and clamping part having projections arranged to extend into the article disposed between them.

3. The combination of a strap or the like and a loop or the like, and a connecting member comprising a web, a looped member extending from one side of the web around a side of the loop or the like and back over the web, a clamping member extending from another side of the web over and holding the strap or the like against said looped member, and a covering member extending from a side of the web over the clamping member.

In testimony whereof I affix my signature.

ZACHARY T. MILLER.
